A CORPORATION OF DELAWARE.

PNEUMATIC FOR MUSICAL INSTRUMENTS.

No. 829,941.

Specification of Letters Patent.

Patented Sept. 4, 1906.

Application filed July 10, 1905. Serial No. 268,912.

To all whom it may concern:

Be it known that I, JACOB BINNIG, a citizen of the United States, residing at Boston, county of Suffolk, and State of Massachusetts, have invented an Improvement in Pneumatics for Musical Instruments, of which the following description, in connection with the accompanying drawings, is a specification, like numerals on the drawings representing like parts.

This invention relates to pneumatics for use in connection with organs, automatic piano-players, and other musical instruments; and it has for its object to provide a novel pneumatic in which the valve system is delicately balanced, so that a minimum amount of force will be required to open the valve of the pneumatic in order to set in operation the power-pneumatic or other device to be operated.

My invention may be embodied in a pneumatic adapted to operate with wind-pressure greater than atmospheric pressure, as well as with wind-pressure less than atmospheric pressure, and in the drawings I have shown my invention as embodied in both of these types of pneumatics.

A device embodying my invention comprises a counterbalancing-chamber which communicates with the wind-chest, two connected valves, one controlling communication between the wind-chest and the device to be operated, which device may be another pneumatic, a power-pneumatic, a pipe-valve, &c., and the other valve controlling communication between said device to be operated and the atmosphere, a counterbalancing-diaphragm which is connected to said valves and which is subjected to the air tension in the wind-chest, and an actuating-diaphragm also connected to said valves and forming one side of an operating-chamber. The valve controlling communication between the wind-chest and the device to be operated is so arranged that the air tension in the wind-chest tends to hold it in its normal position, and this tendency is partially counteracted by the action of the counterbalancing-diaphragm. The size of the valve has such a relation to the size of said diaphragm that these two opposed forces, one tending to hold the valve in its normal position and the other to force the valve out of such position, very nearly, but

not quite, counteract each other, there being a preponderance of pressure on the valve 55 tending to keep it in its normal position. This preponderance of pressure, however, is so slight that a very slight change of pressure or air tension in the operating-chamber is sufficient to overcome it and to throw the valve 60 of the pneumatic quickly and positively.

Figure 1 shows my invention as arranged when the wind-pressure is less than atmospheric. Fig. 2 is a section through the power-pneumatic shown in Fig. 1. Fig. 3 is a view 65 showing a pneumatic embodying my invention adapted for use in connection with wind-pressure greater than atmospheric pressure. Fig. 4 shows another embodiment of my invention in which the pneumatic is operated 70 by wind-pressure less than atmospheric pressure. Fig. 5 is an embodiment of my invention which is adapted for operating a pipe-valve, and Fig. 6 is a modification of Fig. 5.

Referring first to Fig. 1, 3 designates a 75 power-pneumatic, which may be used for any purpose desired—as, for instance, for operating the fingers of an ordinary piano-player. Said power-pneumatic is shown as operated by a secondary pneumatic 4, and said secondary 80 pneumatic is operated by a primary pneumatic 5, which is controlled by means of a perforated sheet 6, passing over a tracker-board 7. The secondary pneumatic herein illustrated comprises a suitable casing 8, divided into 85 two chambers 9 and 10, the communication between which is controlled by a suitable valve 11. The chamber 10 constitutes a counterbalancing-chamber and communicates with a wind-chest 12, having a wind-pressure therein less than atmospheric. The chamber 9 communicates with the atmosphere through a port 13, which is adapted to be closed by a suitable valve 14. Both the valves 11 and 14 are carried by a valve-stem 90 15, which is connected at one end to a counterbalancing-diaphragm 16, closing one end of the counterbalancing-chamber 10, and at the other end to an actuating-diaphragm 17, which forms one side of an operating-chamber 18, communicating with the primary pneumatic. When the pneumatic is operated by pressure less than atmospheric pressure, the wind-chest 12 then becomes an exhaust-chamber, and in this case the valve 11 100 is situated within the chamber 9. With this

arrangement the suction or air tension within the wind-chest 12 operates on the valve 11, tending to close it, and also operates on the counterbalancing-diaphragm 16 with a pressure tending to open said valve, it being understood that the actuating-diaphragm 17 is neutral, it having atmospheric pressure on both sides thereof. The area of said valve 11 and of the counterbalancing-diaphragm 16 5 bear such relation to each other, however, that together with the weight of the valve there is a preponderance of pressure tending to maintain the valve 11 in its normal or closed position, as shown in Fig. 1. This preponderance of pressure, however, is comparatively slight, so that a slight change of pressure in the operating-chamber 18 is sufficient to overcome it and cause the valves of the pneumatic to be operated quickly. The 10 primary pneumatic 5 comprises a suitable casing 20, having a counterbalancing-chamber 21, communicating with a wind-chest 220 of the secondary pneumatic, and a chamber 23, communicating with the atmosphere 15 through a port 24, which is adapted to be closed by a valve 25 and with the counterbalancing-chamber 21, through a port 26, which is adapted to be closed by a valve 27. Both these valves are carried by a suitable 20 valve-stem 28, which is operated by an actuating-diaphragm 29, separating the counterbalancing-chamber 21 from an operating-chamber 22, which communicates through the duct 230 with one of the ducts of the 25 tracker-board 7. The air tension in the wind-chest 220 acts against both the valve 27 and the diaphragm 29, the action against the valve tending to close it and that against the diaphragm tending to open said valve. The 30 area of the valve and diaphragm bear such relation to each other that with the action of gravity on the valve there is a preponderance of pressure tending to keep the valve 27 closed; but this preponderance of pressure is overcome by a slight change of pressure in 35 the chamber 22.

The operation of this device will be apparent from the foregoing, and is as follows: It will be understood, of course, that the 40 actuating-diaphragm 29 is provided with a suitable bleed-hole, so that normally the chamber 22 is exhausted as well as the chamber 21, and the valve 27 is therefore in its normal position or closed by the preponderance of pressure thereon. When, however, an aperture in the perforated sheet 6 passes over the duct in the tracker-board, air is admitted to the chamber 22 and the valve 27 45 opened and valve 25 closed, as will be obvious. When this occurs, the chamber 18 will be exhausted and the diaphragm 17 moved upwardly, (it being understood that the lower side of said diaphragm is always subjected to atmospheric pressure,) thereby closing valve 14 and opening valve 11, thus open-

ing communication between the wind-chest 12 and the pneumatic and exhausting the latter. As soon as the operating-chamber 18 is opened to the atmosphere through the opening of the valve 25 the valve 11 will close and will be held closed by the preponderance of pressure above referred to. 70

Where the wind-pressure in the wind-chest is greater than atmospheric pressure, the valves of a pneumatic embodying my invention are arranged slightly differently from what they are in Fig. 1. Such an arrangement is shown in Fig. 3, wherein 30 designates the device to be operated, which device may be a power-pneumatic or a pipe-valve of an organ, and 31 designates the secondary pneumatic connected to the wind-chest 32, and 33 a primary pneumatic connected to a wind-chest 34. The secondary pneumatic comprises the chamber 35, which 80 connects with the device 30 to be operated, and a counterbalancing-chamber 36, which connects with the wind-chest 32. The communication between the chambers 35 and 36 is controlled by a valve 37, carried by a valve-stem 38, and secured to said valve-stem is another valve 39, which controls communication between the chamber 35 and the atmosphere. Said valve-stem is connected at one end to a counterbalancing-diaphragm 40, 90 which forms one side of the counterbalancing-chamber 36, and at the other end to an actuating-diaphragm 41, forming one side of an operating-chamber 42, which communicates by a suitable conduit 43 with the primary 100 pneumatic. The primary pneumatic is similar in construction to the secondary pneumatic, and is shown as having the chamber 44, with which the conduit 43 communicates, the counterbalancing-chamber 45, communicating with the wind-chest 34, the valve 46, controlling communication between the chambers 45 and 44, and the valve 47, controlling communication between the chamber 44 and the atmosphere. Said valves are connected 105 by the valve-stem 48, which is connected to a counterbalancing-diaphragm 49, subjected to the wind-pressure in the wind-chest 34, and to an actuating diaphragm 50, which is subjected on one side to atmospheric pressure. 115 Beneath the diaphragm 50 is an operating-chamber 51, which communicates by a conduit 52 with one of the ducts of the tracker-board 53, which in this embodiment of my invention is situated within the wind-chest 120 54. The counterbalancing-diaphragm 40 and the valve 37 are both subjected to the pressure of the wind in the wind-chest 32, said wind-pressure operating in opposite directions upon said valve and diaphragm. The 125 area of the valve has such a relation to that of the diaphragm, however, that with the weight of the valves there is a preponderance of pressure on the valve 37, tending to hold it closed, which is its normal position. This 130

preponderance of pressure, however, is only sufficient in amount to keep the valve closed and can be easily overcome by a slight increase of pressure in the chamber 42. The same is true with relation to the valves 46 and 47 of the primary pneumatic, and therefore under normal conditions the valve 46 will be closed. Since these valves are so delicately balanced, it will obviously require a very little pressure in the operating-chambers 42 and 51 to overcome the preponderance of pressure tending to keep the valves closed.

In the operation of this device whenever a hole in the perforated sheet of music uncovers the duct in the tracker-board wind under pressure is admitted to the operating-chamber 51, which wind-pressure acting against the lower side of the actuating-diaphragm 50 overcomes the preponderance of pressure, tending to keep the valve 46 closed, and said valve is therefore opened and wind admitted from the wind-chest 34 of the primary pneumatic directly to the operating-chamber 42 of the secondary pneumatic. The increase of pressure on the under side of the actuating-diaphragm 41 of the secondary pneumatic overcomes the preponderance of pressure tending to keep the inlet-valve 37 closed, whereby said valve is opened, the valve 39 closing at the same time, and wind-pressure is admitted from the wind-chest 32 to the device 30 to be operated.

In Fig. 4 I have shown another embodiment of my invention, which is adapted to be used with wind-pressure less than atmospheric pressure. In said embodiment 3^a is the device to be operated, which is illustrated as a power-pneumatic for operating any suitable device—such, for instance, as a finger of an automatic piano-player. The secondary pneumatic is made with a chamber 65, communicating with the power-pneumatic, a counterbalancing-chamber 66, which connects with the wind-chest 62, and an operating-chamber 63, which communicates with the primary pneumatic, a valve 67 controlling communication between the counterbalancing-chamber 66 and the chamber 65, and another valve 69, which controls communication between said chamber 65 and the atmosphere. Both these valves are attached to a valve-stem 68, and said stem is secured at one end to a counterbalancing-diaphragm 61, forming one side of the counterbalancing-chamber 66, and at the other end to an actuating-diaphragm 64, forming one side of the operating-chamber 63. The primary pneumatic is similar in construction—that is, it includes a chamber 75, communicating with the operating-chamber 63 of the secondary pneumatic, a counterbalancing-chamber 76, communicating with the wind-chest 72, an operating-chamber 73, a valve 77, controlling communication between the chamber 75 and the counterbalancing-chamber, and another

valve 79, controlling communication between said chamber 75 and the atmosphere. Said valves are carried by a valve-stem 78, which is connected at one end to a counterbalancing-diaphragm 71 and at the other end to an actuating-diaphragm 74. The operating-chamber 73 communicates, by a suitable conduit 80, with a duct of the tracker-board 81. In order that the device may operate, it is essential that the operating-chamber be normally exhausted, and to accomplish this purpose I make the tracker-board with a wind-chest or exhaust-chamber 82, which extends the length of the tracker-board and communicates with each of the ducts therein. The normal position of each of the valves 67 and 77 of the primary and secondary pneumatics is the closed position, and the area of each of said valves and the effective area of the corresponding counterbalancing-diaphragms 85 have such relation to each other that there is a preponderance of pressure on each valve tending to hold it in its normal position, which in this embodiment of the invention is the closed position. As soon, however, as an aperture in the perforated music-sheet 83 passes over the duct in the tracker-board air is admitted to the operating-chamber 73 of the primary pneumatic, thus increasing the pressure therein, and such increase of pressure is sufficient to overcome the preponderance of pressure tending to hold the valve 77 closed, whereby said valve opens, the valve 79 closing at the same time, and the pressure in the operating-chamber 63 of the secondary pneumatic is thus reduced, such reduction in pressure being sufficient to overcome the preponderance of pressure tending to hold the valve 67 closed, whereby said valve opens and the power-pneumatic is exhausted.

In Fig. 5 I have illustrated still another embodiment of my invention in which the pneumatics are operated by wind-pressure greater than atmospheric pressure. In all of the forms of my invention heretofore described the normal position of the valve which controls communication between the counterbalancing-chamber and the device to be operated is the closed position. In the embodiment illustrated in Fig. 5 the normal position of said valve is the open position. In the embodiment of the invention shown in Figs. 1, 2, 3, and 4 the device to be operated is a power-pneumatic. In Fig. 5 the device to be operated is a pipe-valve. Said pipe-valve may have any suitable or usual construction and is designated generally by 85. It comprises a diaphragm 86, which controls communication between the wind-chest 87 and the duct 88, leading to the pipe 89. The normal position of the diaphragm 86 is that shown in the drawings, wherein it closes communication between the wind-chest 87 and the duct 88, said diaphragm being held in this position by air-pressure from the ac-

tion wind-chest 90. The secondary pneumatic comprises a counterbalancing-chamber 91, communicating with the action wind-chest 90, a chamber 92, communicating with the pipe-valve, and an operating-chamber 93, which communicates with the primary pneumatic. It also includes an inlet-valve 94, controlling communication between the counterbalancing-chamber and the chamber 92, and another valve 95, controlling communication between the chamber 92 and the atmosphere. Said valves are connected to a valve-stem 96, which is connected at one end to a counterbalancing-diaphragm 97 and at the other end to an actuating-diaphragm 98. The primary pneumatic comprises a chamber 100, communicating with the operating-chamber 93 of the secondary pneumatic, a counterbalancing-chamber 101, an operating-chamber 102, a valve 103, and a valve 104. Said valves are carried by a valve-stem, which is connected at one end to a counterbalancing-diaphragm 105 and at the other end to an actuating-diaphragm 106. 107 designates a wind-chest communicating with the counterbalancing-chamber. In the primary pneumatic the normal position of the inlet-valve 103 is a closed position, while in the secondary pneumatic the normal position 30 is the open position of the valve 94. The operating-chamber 102 of the primary pneumatic is shown as communicating by a conduit 108 with a duct of a tracker-board 109, which is situated within a wind-chest 110. 35 In both the primary and secondary pneumatics the area of the valves 103 and 94 is so arranged with reference to the effective area of the counterbalancing-diaphragm that there is a preponderance of pressure tending 40 to maintain said valves in their normal position, which in the case of the secondary pneumatic is the open position and in the case of the primary pneumatic is the closed position. Whenever wind is admitted to the operating-chamber 102 through the operation of the 45 perforated music-sheet, this preponderance of pressure in the primary pneumatic will be overcome and the valves 103 and 104 will be shifted to admit wind to the operating-chamber 93 of the secondary pneumatic, thereby 50 increasing the pressure in said chamber, such increase of pressure overcoming the preponderance of pressure tending to hold the valve 94 open, whereby said valve closes and the valve 95 opens, thereby to let the wind escape 55 from the pipe-valve. When this occurs, the wind-pressure in the wind-chest 87 lifts the diaphragm 86 from its seat, and wind is admitted to the pipe 89. 60 In Fig. 6 I have illustrated another embodiment of my invention wherein the primary pneumatic is operated by wind having a pressure less than atmospheric pressure. In this embodiment the primary pneumatic 65 comprises a counterbalancing-chamber 111

communicating with a wind-chest 112, in which there is wind having a pressure greater than atmospheric pressure, and an operating-chamber 113. The counterbalancing-chamber and operating-chamber are separated by 70 a counterbalancing-diaphragm 114, which is secured to the valve-stem 115, to which the valve 116 is secured. The valve 116 plays between two valve-seats 117 and 118, and in its normal position, as shown in Fig. 6, it 75 closes communication between the counterbalancing chamber and the conduit 119, leading to the operating-chamber of the secondary pneumatic, and in its abnormal position it closes communication between said 80 conduit and the atmosphere and opens said conduit to the counterbalancing-chamber. The operating-chamber 113 is connected by a conduit 120 to one of the ducts of a tracker-board 121, and associated with said tracker-board is a wind-chest 122, in which the pressure is less than atmospheric pressure. Under normal conditions, therefore, the operating-chamber 113 is exhausted. The valve 116 and the counterbalancing-diaphragm 114 85 have such a size relative to each other that under normal conditions there is a preponderance of pressure on the diaphragm and valve tending to keep the valve against the seat 117, which is the normal position of the 90 valve. Whenever the duct in the tracker-board is uncovered, however, air is admitted to the operating-chamber, thus increasing the pressure therein, with the result that the valve 116 is shifted to its abnormal position and wind from the wind-chest is admitted to the operating-chamber of the secondary pneumatic. 95

In all of the above-described forms of my invention, whether it be embodied in a primary pneumatic or in a secondary pneumatic, it will be noted that the wind-pressure in the wind-chest acts in opposite directions against a connected counterbalancing-diaphragm and valve and that the relative 100 area of said diaphragm and valve is such that there is a preponderance of wind-pressure (or suction) tending to maintain the valve in its normal position; but this preponderance of pressure is so slight that a very small increase of the pressure in the operating-chamber is sufficient to overcome it and cause the valve to operate. In some forms of the invention the normal position of the said valve is the closed position and in other forms it is 105 the open position. 110

One of the advantages gained by my construction is that the valves of each pneumatic work very quickly and are sure to work even though the full wind-pressure is 115 not admitted to the operating-chamber for any reason. This is so because a very slight increase of pressure in the operating-chamber is sufficient to throw the valves. 120

My invention is especially useful in organs, 125

pneumatic piano-players, and similar instruments where a very quick action in the pneumatic is desired.

Another feature of my invention which I consider as important is that all the pneumatics are made entirely of metal, and therefore are not subject to the imperfections inherent in the ordinary form of pneumatic.

It will be noted that the counterbalancing-diaphragm of each pneumatic is secured to the corresponding valve-stem by means of nuts 70, which can be adjusted up and down upon the valve-stem, said stem being screw-threaded for this purpose. By shifting the nuts 70 along the valve-stem thereby to adjust the diaphragm up or down thereon, said diaphragm may be made more or less effective in counteracting the pressure of the wind in the wind-chest on the inlet-valve, tending to hold it in its normal position, for it will be obvious that if the nuts 70 in Fig. 3 were adjusted so as to carry the point of connection of the counterbalancing-diaphragm 40 nearer to the end of the valve-stem said diaphragm would have less lifting power than it has in the position shown in Fig. 3. By means of this construction, therefore, it is possible to adjust the counterbalancing-diaphragms so that the wind-pressure thereagainst will very nearly, but not quite, counterbalance the pressure of the wind against the opposed valve.

Having fully described my invention, what I claim as new, and desire to secure by Letters Patent, is—

1. In a pneumatic action for musical instruments, two connected valves, a counterbalancing-diaphragm and an operating-diaphragm, both connected to said valves.

2. In a device of the class described, a device to be operated, a wind-chest, two connected valves, one to control communication between the wind-chest and the device to be operated, and the other to control communication between said device and the atmosphere, the first-named valve being so located that the pressure within the wind-chest thereagainst tends to hold it in its normal position, and normally operative means acted upon by the tension in the wind-chest to nearly but not quite counterbalance the pressure on said valve.

3. In a device of the class described, a device to be operated, a wind-chest, two connected valves, one controlling communication between said wind-chest and the device to be operated, and the other controlling communication between said device and the atmosphere, a counterbalancing-diaphragm acted on by the air-tension in said wind-chest and operating to approximately counterbalance the action of the air tension against said first-named valve.

4. In a device of the class described, a de-

vice to be operated, a wind-chest, two connected valves, one controlling communication between said wind-chest and the device to be operated, and the other controlling communication between said device and the atmosphere, a counterbalancing-diaphragm acted on by the air tension in said wind-chest and operating to approximately counterbalance the action of the air tension against said first-named valve, and an operating-diaphragm connected to said valve.

5. In a device of the class described, a device to be operated, a wind-chest, a counterbalancing-chamber communicating therewith, a valve controlling communication between said chamber and the device to be operated, said valve being so situated that the air tension in the chamber tends to maintain it in its normal position, a counterbalancing-diaphragm connected to said valve and continuously subjected to the air tension in the wind-chest, whereby the pressure against the diaphragm nearly but not quite counterbalances that against the valve, and an operating-diaphragm also connected to the valve.

6. In a device of the class described, a device to be operated, a wind-chest, a valve-casing having within it two valves connected by a valve-stem, one valve controlling communication between said wind-chest and the device to be operated, and the other valve controlling communication between said device and the atmosphere, a counterbalancing-diaphragm connected to one end of said valve-stem and continuously subjected to the air tension within the wind-chest, and an operating-diaphragm connected at the other end of said valve-stem.

7. In a device of the class described, a casing, two connected valves therein, a counterbalancing-diaphragm at one end of the casing and an operating-diaphragm at the opposite end of the casing, both diaphragms being connected to the valves.

8. In a device of the class described, a metallic casing, two connected valves therein, a counterbalancing-diaphragm at one end of the casing connected to said valves, and an operating-diaphragm at the other end of the casing also connected to said valves.

9. In a device of the class described, a metallic casing connected to the device to be operated and having two ports, two connected valves controlling said ports, a counterbalancing-diaphragm at one end of the casing connected to said valves, and an operating-diaphragm at the other end of the casing also connected to the valves.

10. In a device of the class described, a cylindrical metallic casing having partitions extending thereacross and provided with ports, valves controlling said ports, a valve-stem to which said valves are connected, a counterbalancing-diaphragm at one end of the casing

connected to said valve-stem, an operating-diaphragm at the other end of the casing also connected to said valve-stem, a wind-chest communicating with the casing between the counterbalancing-diaphragm and one valve, and means to vary the pressure on the operating-diaphragm.

In testimony whereof I have signed my name to this specification in the presence of two subscribing witnesses.

JACOB BINNIG.
